US0D1046763S

(12) **United States Design Patent** (10) **Patent No.:** **US D1,046,763 S**
(45) **Date of Patent:** **** Oct. 15, 2024**

(54) **PORTABLE POWER STATION**

(71) Applicant: **Dongguan Chenrui New Energy Technology Co., Ltd.**, Dongguan (CN)

(72) Inventor: **Yongxin Jin**, Dongguan (CN)

(73) Assignee: **Dongguan Chenrui New Energy Technology Co., Ltd.**, Dongguan (CN)

(**) Term: **15 Years**

(21) Appl. No.: **29/856,391**

(22) Filed: **Oct. 13, 2022**

(51) **LOC (14) Cl.** **13-02**

(52) **U.S. Cl.**

USPC **D13/103**

(58) **Field of Classification Search**

USPC D13/103, 104, 106, 107, 108, 110, 112, D13/116, 118, 119, 184, 199; D23/335

CPC H01M 2/1055; H01M 2/20; H02J 7/0044

(57) **CLAIM**

The ornamental design for a portable power station, as shown and described.

DESCRIPTION

FIG. 1 is a front perspective view of a portable power station, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the portable power station, which form no part of the claimed design.
